United States Patent Office.

E. M. HENDRICKSON, OF BROOKLYN, NEW YORK.

Letters Patent No. 99,085, dated January 25, 1870.

IMPROVEMENT IN BURGLAR-PROOF SAFES.

The Schedule referred to in these Letters Patent and making part of the same.

To all whom it may concern:

Be it known that I, E. M. HENDRICKSON, of Brooklyn, county of Kings, and State of New York, have invented a new and useful Improvement in Burglar-Proof Safes; and I do hereby declare that the following is a full, clear, and exact description thereof, which will enable others skilled in the art to make and use the same, reference being had to the accompanying drawing, forming part of this specification.

The object of this invention is to prevent safes for banks, insurance companies, and other institutions, as well as private individuals, and for all purposes for which safes are used, from being blown open by means of powder, nitro-glycerine, or other explosive material or compound; and

The invention consists in forming perforations or apertures in and through some portions of the safe, for the escape of the gas generated by such explosive material, without injuring the safe, as will be herein-after more fully described.

In the accompanying drawing—

Figure 1 is a vertical section of a safe, on the line $x\ x$ of fig. 2.

Figure 2 is a horizontal section of the line $y\ y$ of fig. 1.

Similar letters of reference indicate corresponding parts.

In this example of my invention, I show the bottom of the safe perforated and prepared according to my invention; but I do not confine myself to this particular arrangement, as the auxiliary plates may be more or less in number, or bars or grating may be substituted therefor, and the arrangement may be made in some other part of the safe; but I prefer the bottom, for obvious reasons.

A represents the walls of the safe.

B is the bottom.

C is the top.

D is the door.

The bottom, B, may be perforated with any desired number of holes, or it may be made in any other manner, so that it shall allow the gas from an explosive compound to escape through it.

E represents such apertures.

Above the bottom, and either in contact or separated from each other, I place one or more perforated plates F, with the perforations so arranged, in relation to each other and to the bottom, that the holes shall not register with each other, nor with the holes or perforations E through the bottom. The object of this is to prevent the introduction of a tool or instrument from the bottom, in case the safe should be upset or tipped partly over.

It is evident that if powder or any other explosive material should in any manner be introduced into the safe, and be ignited, the gas would not be confined, but would escape through the bottom and do no injury to the safe.

A portion of the back, top, or any other part of the safe, may be provided with apertures or perforations for the escape of explosive gas for this purpose.

Having thus described my invention,

I claim as new, and desire to secure by Letters Patent—

The construction and arrangement of the perforated plates, as described, whereby the gases from explosive substances may escape, substantially as set forth.

The above specification of my invention signed by me, this 15th day of December, 1869.

E. M. HENDRICKSON.
